(57) **ABSTRACT**

A laminated electronic component includes an element body and a conductor. The element body is formed by laminating a plurality of element-body layers. The element body has a first face, a second face, and a pair of third faces. The conductor is disposed on the element body and has an L shape. The conductor has an exposed face exposed on the first face and the second face. The exposed face includes a plurality of divided regions divided by the element body. The length of each divided region in a dividing direction is longer than a distance with which the plurality of divided regions is separated from each other and longer than a distance with which the exposed face and the pair of third faces are separated from each other.

LAMINATED ELECTRONIC COMPONENT

TECHNICAL FIELD

One aspect of the present invention relates to a laminated electronic component.

BACKGROUND

Japanese Unexamined Patent Publication No. 2002-367833 discloses a laminated electronic component including an element body and a terminal electrode pattern. The element body is formed by laminating a plurality of element-body layers. The terminal electrode pattern is formed in such a way as to be exposed on end faces of the element body. According to the structure of this laminated electronic component, by laminating the terminal electrode pattern together with the element-body layers, it is possible to form an external electrode without using a dipping method.

SUMMARY

In the above laminated electronic component, cracks sometimes occur on the surface of the element body.

One aspect of the present invention is to provide a laminated electronic component in which occurrence of cracks on a surface of an element body is suppressed.

According to the investigation and research by the inventors of the present invention, cracks are easily caused on the surface of the element body by heat treatment in manufacturing the laminated electronic component because the thermal shrinkage percentage of the constituent material of the conductor is larger than the thermal shrinkage percentage of the constituent material of the element body. If the volume of the conductor is reduced, the amount of shrinkage of the constituent material of the conductor is to be lowered. However, as the volume of the conductor decreases, the mounting strength can decrease.

Thus, a laminated electronic component according to one aspect of the present invention includes an element body and a conductor. The element body has a rectangular parallelepiped shape and is formed by laminating a plurality of element-body layers. The element body has a first face, a second face, and a pair of third faces. The second face is adjacent to the first face. The pair of third faces is opposed to each other and is adjacent to the first face and the second face. The conductor is disposed on the element body and has an L shape. The conductor has an exposed face exposed on the first face and the second face. The exposed face includes a plurality of divided regions divided by the element body. The length of each divided region in a dividing direction is longer than a distance with which the plurality of divided regions is separated from each other and longer than a distance with which the exposed face and the pair of third faces are separated from each other.

In this laminated electronic component, the exposed face of the conductor is divided by the element body. Thus, it is possible to relax the stress caused by the difference between the thermal shrinkage percentage of the constituent material of the conductor and the thermal shrinkage percentage of the constituent material of the element body particularly on the surface of the element body. Accordingly, it is possible to suppress occurrence of cracks on the surface of the element body. In addition, in this laminated electronic component, the length of each divided region in the dividing direction is longer than the distance with which the plurality of divided regions is separated from each other and longer than the

2

distance with which the exposed face and the third face are separated from each other. Accordingly, the area of the exposed face is easily kept wide. As a result, it is possible to suppress reduction in the mounting strength.

5 The exposed face may have a first exposed face exposed on the first face and a second exposed face exposed on the second face. The first exposed face and the second exposed face may each include the plurality of divided regions. In this case, it is possible to suppress occurrence of cracks on both the first face and the second face.

The exposed face may be completely divided. In this case, it is possible further to suppress occurrence of cracks.

10 The exposed face may be divided in an opposing direction of the pair of third faces. In this case, the amount of shrinkage per divided region in the opposing direction of the pair of third faces is smaller than the amount of shrinkage of an entire undivided exposed face. Accordingly, it is possible further to suppress occurrence of cracks extending from the exposed face toward the third face.

20

BRIEF DESCRIPTION OF THE DRAWINGS

FIG. 1 is a perspective view of a laminated coil component according to a first embodiment;

25 FIG. 2 is a plan view of the laminated coil component in FIG. 1 when viewed from a mounting surface side;

FIG. 3 is a plan view of the laminated coil component in FIG. 1 when viewed from an end face side;

30 FIG. 4 is an exploded perspective view of the laminated coil component in FIG. 1;

FIG. 5 is a plan view of a laminated coil component according to a second embodiment when viewed from a mounting surface side;

35 FIG. 6 is a plan view of the laminated coil component in FIG. 5 when viewed from an end face side;

FIG. 7 is an exploded perspective view of the laminated coil component in FIG. 5;

40 FIG. 8 is a plan view of a laminated coil component according to a third embodiment when viewed from a mounting surface side;

FIG. 9 is a plan view of the laminated coil component in FIG. 8 when viewed from an end face side;

45 FIG. 10 is an exploded perspective view of the laminated coil component in FIG. 8;

FIG. 11 is a plan view of a laminated coil component according to a fourth embodiment when viewed from a mounting surface side;

50 FIG. 12 is a plan view of the laminated coil component in FIG. 11 when viewed from an end face side; and

FIG. 13 is an exploded perspective view of the laminated coil component in FIG. 11.

DETAILED DESCRIPTION

55 Hereinafter, embodiments will be described in detail with reference to the accompanying drawings. In the following description, the same reference sign is assigned to the same element or the element having the same function, and the redundant description will be omitted.

60

First Embodiment

With reference to FIGS. 1 to 4, a laminated coil component according to a first embodiment is described. FIG. 1 is a perspective view of the laminated coil component according to the first embodiment. FIG. 2 is a plan view of the laminated coil component in FIG. 1 when viewed from a

mounting surface side. FIG. 3 is a plan view of the laminated coil component in FIG. 1 when viewed from an end face side. FIG. 4 is an exploded perspective view of the laminated coil component in FIG. 1. With reference to FIGS. 1 to 4, a laminated coil component 1 according to the first embodiment includes an element body 2, a pair of conductors 3, a plurality of coil conductors 5c, 5d, 5e, and 5f, and connecting conductors 6 and 7.

The element body 2 has a rectangular parallelepiped shape. The rectangular parallelepiped shape includes a rectangular parallelepiped shape in which the corner portions and the ridge portions are chamfered, and a rectangular parallelepiped shape in which the corner portions and the ridge portions are rounded. The element body 2 has end faces 2a and 2b, and side faces 2c, 2d, 2e, and 2f. The end faces 2a and 2b are opposed to each other. The side faces 2c and 2d are opposed to each other. The side faces 2e and 2f are opposed to each other. In the following description, it is assumed that the opposing direction of the end faces 2a and 2b is a direction D1, that the opposing direction of the side faces 2c and 2d is a direction D2, and that the opposing direction of the side faces 2e and 2f is a direction D3. The direction D1, the direction D2, and the direction D3 are substantially orthogonal to each other.

The end faces 2a and 2b extend in the direction D2 in such a way as to connect the side faces 2c and 2d. The end faces 2a and 2b also extend in the direction D3 in such a way as to connect the side faces 2e and 2f. The side faces 2c and 2d extend in the direction D1 in such a way as to connect the end faces 2a and 2b. The side faces 2c and 2d also extend in the direction D3 in such a way as to connect the side faces 2e and 2f. The side faces 2e and 2f extend in the direction D2 in such a way as to connect the side faces 2c and 2d. The side faces 2e and 2f also extend in the direction D1 in such a way as to connect the end faces 2a and 2b.

The side face 2c is a mounting surface and is opposed to another electronic device, which is not shown, (for example, a circuit substrate or a laminated electronic component) when, for example, the laminated coil component 1 is mounted on the electronic device. The end faces 2a and 2b are faces adjacent to the mounting surface (that is, the side face 2c).

The length of the element body 2 in the direction D1 is longer than the length of the element body 2 in the direction D2 and the length of the element body 2 in the direction D3. The length of the element body 2 in the direction D2 and the length of the element body 2 in the direction D3 are equivalent to other. That is, in the present embodiment, the end faces 2a and 2b each have a square shape, and the side faces 2c, 2d, 2e, and 2f each have a rectangular shape. The length of the element body 2 in the direction D1 may be equivalent to the length of the element body 2 in the direction D2 and to the length of the element body 2 in the direction D3, or may be shorter than these lengths. The length of the element body 2 in the direction D2 and the length of the element body 2 in the direction D3 may be different from each other.

In the present embodiment, the term "equivalent" may include, in addition to being equal, a value including a slight difference or a manufacturing error in a preset range. For example, if a plurality of values is included within the range of $\pm 5\%$ of the average value of the values, the values are defined to be equivalent.

The element body 2 is constituted by laminating a plurality of element-body layers 12a to 12f in the direction D3. That is, the lamination direction of the element body 2 is the direction D3. A specific laminated structure will be

described later. In the actual element body 2, the element-body layers 12a to 12f are integrated in such a way that no boundaries between the layers cannot be visually recognized. The element-body layers 12a to 12f includes, for example, a magnetic material (Ni—Cu—Zn-based ferrite material, Ni—Cu—Zn—Mg-based ferrite material, Ni—Cu-based ferrite material, or the like). The magnetic material forming the element-body layers 12a to 12f may contain Fe alloy or the like. The element-body layers 12a to 12f may include a non-magnetic material (a glass ceramic material, a dielectric material, or the like).

The pair of conductors 3 is disposed on the element body 2. Specifically, the pair of conductors 3 is disposed in depressions provided on the outer surface of the element body 2, and is exposed on the outer surface of the element body 2. The pair of conductors 3 is separated from each other in the direction D3. When viewed from the direction D3, each conductor 3 has an L shape. Each conductor 3 has a conductor portion 31 and a conductor portion 32 which are integrally provided. When viewed from the direction D3, the conductor portion 31 extends in the direction D1 and the conductor portion 32 extends in the direction D2. The conductor portion 31 is disposed in a depression provided on the side face 2c. The conductor portion 32 is disposed in a depression provided on each of the end faces 2a and 2b. The conductor portions 31 and 32 each have a substantially rectangular plate shape. The pair of conductors 3 has the same shape. The L shape may be any shape as long as it is a substantially L shape as a whole. For example, the L shape may have depressions and projections provided on the surface of each conductor 3 as long as it is a substantially L shape as a whole. Each conductor 3 is only required to have a substantially L shape as a whole in a case in which the conductor is provided continuously or intermittently.

The pair of conductors 3 has a pair of exposed faces 3a exposed on the side face 2c and the end faces 2a and 2b. Specifically, one conductor 3 has one exposed face 3a exposed on the side face 2c and the end face 2a. Another conductor 3 has another exposed face 3a exposed on the side face 2c and the end face 2b. The one exposed face 3a includes an exposed face 31a exposed on the side face 2c and an exposed face 32a exposed on the end face 2a. The other exposed face 3a includes an exposed face 31a exposed on the side face 2c and an exposed face 32a exposed on the end face 2b. Here, the exposed face 31a is a face of the conductor portion 31. The exposed face 32a is a face of the conductor portion 32. The exposed faces 31a and 32a have the same shape.

The exposed face 31a may be positioned in the same plane as the side face 2c. The exposed face 31a may be positioned at an inner side or an outer side of the element body 2 as compared with the side face 2c. The exposed face 32a may be positioned in the same plane as the end face 2a or 2b. The exposed face 31a may be positioned at an inner side or an outer side of the element body 2 with respect to the end face 2a or 2b. The exposed faces 31a and 32a are disposed at equal distances from the side faces 2e and 2f.

The exposed face 3a includes a plurality of divided regions R1 to R4 divided by the element body 2. Specifically, the exposed face 31a includes the divided regions R1 and R2 divided by the element body 2. The exposed face 32a includes the divided regions R3 and R4 divided by the element body 2. The divided regions R1 to R4 have the same shape. The divided regions R1 to R4 each have a rectangular shape.

The divided regions R1 and R2 are divided in the direction D3 and separated from each other in the direction D3.

The dividing direction of the divided regions R1 and R2 and the separating direction of the divided regions R1 and R2 are the same as the lamination direction of the element-body layers 12a to 12f which is the direction D3. That is, it can be said that the exposed face 31a is divided in the lamination direction of the element-body layers 12a to 12f. The divided regions R1 and R2 are not connected to each other, and the exposed face 31a is completely divided.

The divided regions R3 and R4 are divided in the direction D3 and separated from each other in the direction D3. The dividing direction of the divided regions R3 and R4 and the separating direction of the divided regions R3 and R4 are the same as the lamination direction of the element-body layers 12a to 12f which is the direction D3. That is, it can be said that the exposed face 32a is divided in the lamination direction of the element-body layers 12a to 12f. The divided regions R3 and R4 are not connected to each other, and the exposed face 32a is completely divided.

The divided regions R1 and R3 are disposed by the side of the side face 2e (closer to the side face 2e than the side face 2f) and are connected to each other. The divided regions R1 and R3 are connected to each other at a ridge portion of the element body 2 (hereinafter, also referred to as a ridge portion of the side face 2c) at which the side face 2c and the end face 2a or 2b are connected to each other. The divided regions R2 and R4 are disposed by the side of the side face 2f (closer to the side face 2f than the side face 2e) and are connected to each other. The divided regions R2 and R4 are connected to each other at the ridge portion of the side face 2c. That is, the exposed faces 31a and 32a are connected to each other at the ridge portion of the side face 2c.

The length L1 of each of the divided regions R1 and R2 in the direction D3 is longer than the distance L2 with which the divided regions R1 and R2 are separated from each other and longer than the distance L3 with which the exposed face 31a and the side face 2e or 2f are separated from each other. The length L1 of each of the divided regions R3 and R4 in the direction D3 is longer than the distance L2 with which the divided regions R3 and R4 are separated from each other and longer than the distance L3 with which the exposed face 32a and the side face 2e or 2f are separated from each other.

In each conductor 3, at least the exposed face 3a is only required to be divided by the element body 2, and portions other than the exposed face 3a may be connected to each other. In each conductor 3 in the present embodiment, not only the exposed face 3a but also the whole in a thickness direction of the conductor 3 is divided by the element body 2. The thickness direction of the conductor 3 is the direction D2 for the conductor portion 31 and the direction D1 for the conductor portion 32. Thus, the conductor portion 31 is completely divided by the element body 2 into a portion having the divided region R1 and a portion having the divided region R2. The conductor portion 32 is completely divided by the element body 2 into a portion having the divided region R3 and a portion having the divided region R4.

Each conductor 3 is formed by laminating a plurality of conductor layers 13 in the direction D3. That is, the lamination direction of the conductor layers 13 is the direction D3. In the actual conductor 3, the conductor layers 13 other than the portion divided by the element body 2 are integrated in such a way that no boundaries between the layers can be visually recognized.

Each conductor 3 may be provided with a plating layer (not shown) containing, for example, Ni, Sn, Au, or the like by electrolytic plating or electroless plating. The plating layer may have, for example, a Ni plating film and an Au

plating film. The Ni plating film contains Ni and covers the conductor 3. The Au plating film contains Au and covers the Ni plating film.

The coil conductors 5c to 5f shown in FIG. 1 are connected to each other to form a coil 10 in the element body 2. The coil axis of the coil 10 is provided along the direction D3. The coil conductors 5c to 5f are disposed in such a way as to at least partially overlap each other when viewed from the direction D3. The coil conductors 5c to 5f are disposed apart from the end faces 2a and 2b and the side faces 2c, 2d, 2e, and 2f.

The coil conductors 5c to 5f are constituted by a group of coil conductor layer 15c, 15d, 15e, and 15f. The coil conductors 5c to 5f may be constituted by laminating a plurality of groups of coil conductor layers 15c, 15d, 15e, and 15f in the direction D3. In this case, the groups of the coil conductor layers 15c to 15f are disposed in such a way as to entirely overlap each other when viewed from the direction D3. In this manner, by laminating the groups of coil conductor layers 15c to 15f, it is possible to increase the aspect ratio of the coil conductors 5c to 5f and to improve the Q-value of the coil 10.

The connecting conductor 6 extends in the direction D1. The connecting conductor 6 is connected to the coil conductor 5c and another conductor portion 32. The connecting conductor 7 extends in the direction D1. The connecting conductor 7 is connected to the coil conductor 5f and the one conductor portion 32. The connecting conductors 6 and 7 are constituted by a group of connecting conductor layers 16 and 17. The connecting conductors 6 and 7 may be constituted by laminating a plurality of groups of connecting conductor layers 16 and 17 in the direction D3. In this case, the groups of the connecting conductor layers 16 and 17 are disposed in such a way as to entirely overlap each other when viewed from the direction D3.

The conductor layers 13, the coil conductor layers 15c, 15d, 15e, and 15f, and the connecting conductor layers 16 and 17 includes a conductive material (for example, Ag or Pd). Each layer may include the same material or different materials.

The laminated coil component 1 has layers La, Lb, Lc, Ld, Le, and Lf. For example, the laminated coil component 1 is constituted by laminating, from the side face 2f side, one layer La, two layers Lb, one layer Lc, one layer Ld, one layer Le, one layer Lf, two layers Lb, and one layer La, in this order.

The layer La is constituted by the element-body layer 12a.

The layer Lb is constituted by combining the element-body layer 12b and a pair of conductor layers 13 with each other. The element-body layer 12b is provided with a defect portion Rb. The defect portion Rb has shapes corresponding to the respective shapes of the pair of conductor layers 13. The pair of conductor layers 13 is fitted into the defect portion Rb. The element-body layer 12b and the pair of conductor layers 13 have mutually complementary relationship as a whole.

The layer Lc is constituted by combining the element-body layer 12c, a pair of conductor layers 13, the coil conductor layer 15c, and the connecting conductor layer 16 with each other. The element-body layer 12c is provided with a defect portion Rc. The defect portion Rc has shapes corresponding to the respective shapes of the pair of conductor layers 13, the coil conductor layer 15c, and the connecting conductor layer 16. The pair of the conductor layers 13, the coil conductor layer 15c, and the connecting conductor layer 16 are fitted into the defect portion Rc. The element-body layer 12c, the pair of conductor layers 13, the

coil conductor layer **15c**, and the connecting conductor layer **16** have mutually complementary relationship as a whole.

The layer **Ld** is constituted by combining the element-body layer **12d**, and the coil conductor layer **15d** with each other. The element-body layer **12d** is provided with a defect portion **Rd**. The defect portion **Rd** has shape corresponding to the shape of the coil conductor layer **15d**. The coil conductor layer **15d** is fitted into the defect portion **Rd**. The element-body layer **12d**, and the coil conductor layer **15d** have mutually complementary relationship as a whole.

The layer **Le** is constituted by combining the element-body layer **12e**, and the coil conductor layer **15e** with each other. The element-body layer **12e** is provided with a defect portion **Re**. The defect portion **Re** has shape corresponding to the shapes of the coil conductor layer **15e**. The coil conductor layer **15e** is fitted into the defect portion **Re**. The element-body layer **12e**, and the coil conductor layer **15e** have mutually complementary relationship as a whole.

The layer **Lf** is constituted by combining the element-body layer **12f**, a pair of conductor layers **13**, the coil conductor layer **15f**, and the connecting conductor layer **17** with each other. The element-body layer **12f** is provided with a defect portion **Rf**. The defect portion **Rf** has shapes corresponding to the respective shapes of the pair of conductor layers **13**, the coil conductor layer **15f**, and the connecting conductor layer **17**. The pair of the conductor layers **13**, the coil conductor layer **15f**, and the connecting conductor layer **17** are fitted into the defect portion **Rf**. The element-body layer **12f**, the pair of conductor layers **13**, the coil conductor layer **15f**, and the connecting conductor layer **17** have mutually complementary relationship as a whole.

The widths of the defect portions **Rb**, **Re**, **Rd**, **Re**, and **Rf** (hereinafter, the width of the defect portion) are basically set in such a way as to be wider than the those of the conductor layers **13**, the coil conductor layers **15c**, **15d**, **15e**, and **15f**, and the connecting conductor layers **16** and **17** (hereinafter, the width of the conductor portion). The width of the defect portion may be intentionally set in such a way as to be narrower than the width of the conductor portion in order for the element-body layers **12b**, **12c**, **12d**, **12e**, and **12f** to adhere to the conductor layers **13**, the coil conductor layers **15c**, **15d**, **15e**, and **15f**, and the connecting conductor layers **16** and **17** more firmly. The value obtained by subtracting the width of the conductor portion from the width of the defect portion is preferably, for example, -3 μm or more and 10 μm or less, and more preferably 0 μm or more and 10 μm or less.

An example of a method for manufacturing the laminated coil component **1** according to the embodiment is described.

First, an element-body paste containing the constituent material of the element-body layers **12a** to **12f** and a photosensitive material is applied on a substrate (for example, a PET film). An element-body forming layer is thereby formed. The photosensitive material contained in the element-body paste may be either a negative type or a positive type, and a known photosensitive material can be used. Then, the element-body forming layer is exposed and developed by, for example, a photolithography method using a Cr mask. An element-body pattern from which a shape corresponding to the shape of a conductor forming layer to be described later is removed is thereby formed on the substrate. The element-body pattern is a layer to be each of the element-body layers **12b**, **12c**, **12d**, **12e**, and **12f** after heat treatment. That is, the element-body pattern provided with defect portions to be the defect portions **Rb**, **Rc**, **Rd**, **Re**, and **Rf** is formed. Note that, the "photolithography method" in the present embodiment is only required to be a method for forming a desired pattern by exposing and developing a

layer to be patterned containing a photosensitive material, and is not limited to the type of mask or the like.

On the other hand, a conductor paste containing the constituent materials of the above conductor layer **13**, the coil conductor layers **15c**, **15d**, **15e**, and **15f**, and the connecting conductor layers **16** and **17**, and a photosensitive material is applied on a substrate (for example, a PET film). A conductor forming layer is thereby formed. The photosensitive material contained in the conductor paste may be either a negative type or a positive type, and a known photosensitive material can be used. Then, the conductor forming layer is exposed and developed by, for example, a photolithography method using a Cr mask. A conductor pattern is thereby formed on the substrate. The conductor pattern is a layer to be each of the conductor layer **13**, the coil conductor layers **15c**, **15d**, **15e**, and **15f**, and the connecting conductor layers **16** and **17** after the heat treatment.

Then, the element-body forming layer is transferred from the substrate onto a supporting body. The layer **La** after the heat treatment is thereby formed.

Then, the conductor pattern and the element-body pattern are repeatedly transferred onto the supporting body. The conductor patterns and the element-body patterns are thereby laminated in the direction **D3**. Specifically, first, the conductor pattern is transferred from the substrate onto the element-body forming layer. Next, the element-body pattern is transferred from the substrate onto the element-body forming layer. The conductor pattern is combined with the defect portion of the element-body pattern, and the element-body pattern and the conductor pattern are in the same layer on the element-body forming layer. The step of transferring the conductor pattern and element-body pattern is further repeated. The conductor pattern and the element-body pattern are thereby laminated in a state of being combined with each other. The layers to be the layers **Lb**, **Lc**, **Ld**, **Le**, and **Lf** after the heat treatment are thereby laminated.

Then, the element-body forming layer is transferred from the substrate onto the layers laminated in the steps of transferring the conductor pattern and the element-body pattern. The layer **La** after the heat treatment is thereby laminated.

As described above, a laminate constituting the laminated coil component **1** is formed on the supporting body after the heat treatment. Then, the obtained laminate is cut into a predetermined size. Thereafter, the cut laminate is subjected to debinding treatment, and then subjected to the heat treatment. The temperature of the heat treatment is, for example, about 850 to 900 $^{\circ}\text{C}$. The laminated coil component **1** is thereby obtained. As necessary, the conductor **3** may be provided with a plating layer by electrolytic plating or electroless plating after the heat treatment.

As described above, in the laminated coil component **1**, the exposed face **3a** of each conductor **3** is divided in the direction **D3** by the element body **2**. Thus, it is possible to relax the stress caused by the difference between the thermal shrinkage percentage of the constituent material of the conductor **3** and the thermal shrinkage percentage of the constituent material of the element body **2** particularly on the surface of the element body **2**. That is, the stress of the exposed face **3a** pulling the surface of the element body **2** due to the thermal shrinkage of the constituent material of the conductor **3** is dispersed in the respective divided regions **R1** to **R4**. Accordingly, it is possible to suppress occurrence of cracks on the surface of the element body **2**. Since the exposed face **3a** of each conductor **3** is divided by the element body **2**, the contact area between the conductor **3**

and the element body 2 is increased, and the fixing strength between the conductor 3 and the element body 2 is improved.

In the laminated coil component 1, the length L1 of each of the divided regions R1 and R2 in the direction D3 is longer than the distance L2 with which the divided regions R1 and R2 are separated from each other and longer than the distance L3 with which the exposed face 31a and the side face 2e or 2f are separated from each other. The length L1 of each of the divided regions R3 and R4 in the direction D3 is longer than the distance L2 with which the divided regions R3 and R4 are separated from each other and longer than the distance L3 with which the exposed face 32a and the side face 2e or 2f are separated from each other. Accordingly, the area of the exposed face 3a is easily kept wider as compared with the case in which, for example, the length L1 is shorter than the distances L2 and L3. As a result, it is possible to suppress reduction in the mounting strength when the laminated coil component 1 is mounted on an electronic device by the conductor 3.

The exposed face 3a includes the exposed face 31a including the divided regions R1 and R2, and the exposed face 32a including the divided regions R3 and R4. Thus, it is possible to suppress occurrence of cracks on the side face 2e on which the exposed face 31a is exposed and on each of the end faces 2a and 2b on which the exposed face 32a is exposed.

The divided regions R1 and R2 are not connected to each other, and the exposed face 31a is completely divided. The divided regions R3 and R4 are not connected to each other, and the exposed face 32a is completely divided. Thus, it is possible to further suppress occurrence of cracks on the side face 2c and the end faces 2a and 2b.

The exposed faces 31a and 32a are divided in the direction D3 which is the opposing direction of the side faces 2e and 2f. Thus, the amount of shrinkage of each of the divided regions R1 to R4 in the direction D3 is smaller than the amount of shrinkage of the undivided exposed faces 31a and 32a as a whole. Accordingly, it is possible to further suppress occurrence of cracks extending from the ends at the side faces 2e and 2f sides of the exposed faces 31a and 32a toward the side faces 2e and 2f.

Second Embodiment

With reference to FIGS. 5 to 7, a laminated coil component according to a second embodiment will be described. FIG. 5 is a plan view of the laminated coil component according to the second embodiment when viewed from a mounting surface side. FIG. 6 is a plan view of the laminated coil component in FIG. 5 when viewed from an end face 2a side. FIG. 7 is an exploded perspective view of the laminated coil component in FIG. 5. As shown in FIGS. 5 to 7, a laminated coil component 1A according to the second embodiment differs from the laminated coil component 1 according to the first embodiment (see FIG. 1) mainly in that exposed faces 31a and 32a of each conductor 3 are not completely divided. The laminated coil component 1A will be described below focusing on differences from the laminated coil component 1.

In the laminated coil component 1A, the exposed face 31a includes divided regions R1 and R2 and a connection region R5. The connection region R5 connects the divided region R1 to the divided region R2. That is, the exposed face 31a is not completely divided. The exposed face 32a includes divided regions R3 and R4 and a connection region R6. The

connection region R6 connects the divided region R3 to the divided region R4. That is, the exposed face 32a is not completely divided.

In the laminated coil component 1A, each conductor 3 is formed by laminating a plurality of conductor layers 18 in the direction D3 in addition to a plurality of conductor layers 13. Each conductor layer 18 has a pair of exposed faces. One exposed face is exposed on a side face 2c to be the connection region R5. Another exposed face is exposed to an end face 2a or 2b to be the connection region R6. The lamination direction of the conductor layers 13 and the conductor layers 18 is the direction D3. The connection regions R5 and R6 have the same shape. The connection regions R5 and R6 are connected to each other at the ridge portion of the side face 2c.

In the laminated coil component 1 (see FIG. 4), the layer Ld is constituted by combining the element-body layer 12d, and the coil conductor layer 15d with each other. In contrast, in the laminated coil component 1A, the layer Ld is constituted by combining the element-body layer 12d, the coil conductor layer 15d, and the conductor layer 18 with each other. The defect portion Rd has shapes corresponding to the respective shapes of the coil conductor layer 15d, and the conductor layer 18. The coil conductor layer 15d, and the conductor layer 18 are fitted into the defect portion Rd.

In the laminated coil component 1 (see FIG. 4), the layer Le is constituted by combining the element-body layer 12e, and the coil conductor layer 15e with each other. In contrast, in the laminated coil component 1A, the layer Le is constituted by combining the element-body layer 12e, the coil conductor layer 15e, and the conductor layer 18 with each other. The defect portion Re has shapes corresponding to the respective shapes of the coil conductor layer 15e, and the conductor layer 18. The coil conductor layer 15e, and the conductor layer 18 are fitted into the defect portion Re.

Also in the laminated coil component 1A, it is possible to obtain effects similar to those of the laminated coil component 1 (see FIG. 1). That is, since the exposed face 3a is divided, it is possible to suppress occurrence of cracks on the surface of the element body 2. Since the length L1 is longer than the distances L2 and L3, the area of the exposed face 3a is easily kept wide, and it is possible to suppress reduction in the mounting strength. Since both the exposed faces 31a and 32a are divided, it is possible to suppress occurrence of cracks on the side face 2c and the end faces 2a and 2b. Since the exposed faces 31a and 32a are divided in the direction D3, it is possible to further suppress occurrence of cracks extending from the ends at the side faces 2e and 2f sides of the exposed faces 31a and 32a toward the side faces 2e and 2f.

Since the exposed face 3a includes the connection region R5 or R6, the laminated coil component 1A has a larger area of the exposed face 3a than that of the laminated coil component 1. Thus, it is possible to more reliably suppress reduction in the mounting strength.

Third Embodiment

With reference to FIGS. 8 to 10, a laminated coil component according to a third embodiment will be described. FIG. 8 is a plan view of the laminated coil component according to the third embodiment when viewed from a mounting surface side. FIG. 9 is a plan view of the laminated coil component in FIG. 8 when viewed from an end face 2a side. FIG. 10 is an exploded perspective view of the laminated coil component in FIG. 8. As shown in FIGS. 8 to 10, a laminated coil component 1B according to the third

11

embodiment differs from the laminated coil component 1 according to the first embodiment (see FIG. 1) mainly in that an exposed face 31a is also divided in the direction D1 in addition to the direction D3 and that an exposed face 32a is also divided also in the direction D2 in addition to the direction D3. The laminated coil component 1B will be described below focusing on differences from the laminated coil component 1.

In the laminated coil component 1B, the exposed face 31a is divided in the direction D3 and the direction D1 by an element body 2. Accordingly, the exposed face 31a includes a plurality of divided regions R7, R8, R9, and R10 that are divided in a grid or a matrix. The exposed face 32a is divided in the direction D3 and the direction D2 by the element body 2. Accordingly, the exposed face 32a includes a plurality of divided regions R11, R12, R13, and R14 divided in a grid or a matrix. The divided regions R7 to R14 have the same shape. The divided regions R7 to R14 each have a rectangular shape.

The divided regions R7 and R8 are divided in the direction D3 and separated from each other in the direction D3. The divided regions R9 and R10 are divided in the direction D3 and separated from each other in the direction D3. The divided regions R7 and R9 are divided in the direction D1 and separated from each other in the direction D1. The divided regions R8 and R10 are divided in the direction D1 and separated from each other in the direction D1. The divided regions R7 to R10 are not connected to each other, and the exposed face 31a is completely divided.

The divided regions R11 and R12 are divided in the direction D3 and separated from each other in the direction D3. The divided regions R13 and R14 are divided in the direction D3 and separated from each other in the direction D3. The divided regions R11 and R13 are divided in the direction D2 and separated from each other in the direction D2. The divided regions R12 and R14 are divided in the direction D2 and separated from each other in the direction D2. The divided regions R11 to R14 are not connected to each other, and the exposed face 32a is completely divided.

The divided regions R7, R9, R11, and R13 are disposed by the side of the side face 2e (closer to the side face 2e than the side face 2f). The divided regions R9 and R13 are connected to each other at the ridge portion of the side face 2c. The divided regions R8, R10, R12, and R14 are disposed by the side of the side face 2f (closer to the side face 2f than the side face 2e). The divided regions R10 and R14 are connected to each other at the ridge portion of the side face 2c.

The length L1 of each of the divided regions R7 to R10 in the direction D3 is longer than the distance L2 with which the divided regions R7 and R8 are separated from each other, longer than the distance L2 with which the divided regions R9 and R10 are separated from each other, and longer than the distance L3 with which the exposed face 31a and the side face 2e or 2f are separated from each other. The length L4 of each of the divided regions R7 to R10 in the direction D1 is longer than the distance L5 with which the divided regions R7 and R9 are separated from each other, longer than the distance L5 with which the divided regions R8 and R10 are separated from each other, and longer than the distance L3 with which the exposed face 31a and the side face 2e or 2f are separated from each other.

The length L1 of each of the divided regions R11 to R14 in the direction D3 is longer than the distance L2 with which the divided regions R11 and R12 are separated from each other, longer than the distance L2 with which the divided regions R13 and R14 are separated from each other, and

12

longer than the distance L3 with which the exposed face 32a and the side face 2e or 2f are separated from each other. The length L4 of each of the divided regions R11 to R14 in the direction D2 is longer than the distance L5 with which the divided regions R11 and R13 are separated from each other, longer than the distance L5 with which the divided regions R12 and R14 are separated from each other, and longer than the distance L3 with which the exposed face 32a and the side face 2e or 2f are separated from each other.

Also in the laminated coil component 1B, it is possible to obtain effects similar to those of the laminated coil component 1 (see FIG. 1). That is, since the exposed face 3a is divided, it is possible to suppress occurrence of cracks on the surface of the element body 2. Since the length L1 is longer than the distances L2 and L3 and the length L4 is longer than the distances L5 and L3, the area of the exposed face 3a is easily kept wide, and it is possible to suppress reduction in the mounting strength. Since both the exposed faces 31a and 32a are divided, it is possible to suppress occurrence of cracks on the side face 2c and the end faces 2a and 2b. Since the exposed faces 31a and 32a are divided in the direction D3, it is possible to further suppress occurrence of cracks extending from the ends at the side faces 2e and 2f sides of the exposed faces 31a and 32a toward the side faces 2e and 2f.

In the laminated coil component 1B, the exposed face 31a is also divided in the direction D1 in addition to the direction D3, and the exposed face 32a is also divided in the direction D2 in addition to the direction D3. Thus, the area of the divided regions R7 to R14 is smaller than that of the divided regions R1 to R4 (see FIGS. 2 and 3). Thus, the stress caused by the difference between the thermal shrinkage percentage of the constituent material of the conductor 3 and the thermal shrinkage percentage of the constituent material of the element body 2 is further relaxed on the surface of the element body 2. As a result, it is possible to further suppress occurrence of cracks on the surface of the element body 2.

Fourth Embodiment

With reference to FIGS. 11 to 13, a laminated coil component according to a fourth embodiment will be described. FIG. 11 is a plan view of the laminated coil component according to the fourth embodiment when viewed from a mounting surface side. FIG. 12 is a plan view of the laminated coil component in FIG. 11 when viewed from an end face 2a side. FIG. 13 is an exploded perspective view of the laminated coil component in FIG. 11. As shown in FIGS. 11 to 13, a laminated coil component 1C according to the fourth embodiment differs from the laminated coil component 1B according to the third embodiment (See FIGS. 8 and 9) in that exposed faces 31a and 32a are not divided in the direction D3. The laminated coil component 1C will be described below focusing on differences from the laminated coil components 1 and 1B.

In the laminated coil component 1C, the exposed face 31a includes a plurality of divided regions R15 and R16 divided in the direction D1 by an element body 2. The exposed face 32a includes a plurality of divided regions R17 and R18 divided in the direction D2 by the element body 2. The divided regions R15 to R18 have the same shape. The divided regions R15 to R18 each have a rectangular shape.

The divided regions R15 and R16 are divided in the direction D1 and separated from each other in the direction D1. The divided regions R17 and R18 are divided in the direction D2 and separated from each other in the direction D2. The divided regions R15 and R16 are not connected to

13

each other, and the exposed face **31a** is completely divided. The divided regions **R17** and **R18** are not connected to each other, and the exposed face **32a** is completely divided.

The divided regions **R16** and **R18** are connected to each other at the ridge portion of a side face **2c**.

The length **L4** of each of the divided regions **R15** and **R16** in the direction **D1** is longer than the distance **L5** with which the divided regions **R15** and **R16** are separated from each other and longer than the distance **L3** with which the exposed face **31a** and the side face **2e** or **2f** are separated from each other. The length **L4** of each of the divided regions **R17** and **R18** in the direction **D2** is longer than the distance **L5** with which the divided regions **R17** and **R18** are separated from each other and longer than the distance **L3** with which the exposed face **32a** and the side face **2e** or **2f** are separated from each other. The length **L6** of each of the divided regions **R15** to **R18** in the direction **D3** is equivalent to the sum of twice the length **L1** (see FIGS. 8 and 9) and the distance **L2** (see FIGS. 8 and 9).

In the laminated coil component **1** (see FIG. 4), the layer **Ld** is constituted by combining the element-body layer **12d**, and the coil conductor layer **15d** with each other. In contrast, in the laminated coil component **1C**, the layer **Ld** is constituted by combining the element-body layer **12d**, the coil conductor layer **15d**, and the conductor layer **13** with each other. The defect portion **Rd** has shapes corresponding to the respective shapes of the coil conductor layer **15d**, and the conductor layer **13**. The coil conductor layer **15d**, and the conductor layer **13** are fitted into the defect portion **Rd**.

In the laminated coil component **1** (see FIG. 4), the layer **Le** is constituted by combining the element-body layer **12e**, and the coil conductor layer **15e** with each other. In contrast, in the laminated coil component **1C**, the layer **Le** is constituted by combining the element-body layer **12e**, the coil conductor layer **15e**, and the conductor layer **13** with each other. The defect portion **Re** has shapes corresponding to the respective shapes of the coil conductor layer **15e**, and the conductor layer **13**. The coil conductor layer **15e**, and the conductor layer **13** are fitted into the defect portion **Re**.

Also in the laminated coil component **1C**, it is possible to obtain effects similar to those of the laminated coil component **1** (see FIG. 1). That is, since the exposed face **3a** is divided, it is possible to suppress occurrence of cracks on the surface of the element body **2**. Since the length **L4** is longer than the distances **L5** and **L3**, the area of the exposed face **3a** is easily kept wide, and it is possible to suppress reduction in the mounting strength. Since both the exposed faces **31a** and **32a** are divided, it is possible to suppress occurrence of cracks on the side face **2c** and the end faces **2a** and **2b**.

The present invention is not limited to the above embodiments, and various modifications can be made.

In the laminated coil components **1**, **1A**, **1B**, and **1C**, for example, the pair of conductors **3** may have different shapes from each other, and at least one of the pair of conductors **3** is only required to have the divided exposed face **3a**. The exposed faces **31a** and **32a** may have different shapes from each other. At least one of the exposed faces **31a** and **32a** is only required to be divided. Each divided region may not have the same shape. Each divided region may have a shape other than a rectangular shape. The exposed faces **31a** and **32a** may not be connected to each other but may be divided at the ridge portion of the side face **2c**.

In the laminated coil components **1**, **1A**, the exposed faces **31a** and **32a** are each divided into two divided regions in the direction **D3**, but may be divided into three or more divided regions. In the laminated coil component **1C**, the exposed

14

face **31a** is divided into two divided regions in the direction **D1**, but may be divided into three or more divided regions. The exposed face **32a** is divided into two divided regions in the direction **D2**, but may be divided into three or more divided regions. In the laminated coil component **1B**, the exposed faces **31a** and **32a** are each divided in a grid or a matrix, but may be further divided finely. In such a case, it is possible to further suppress occurrence of cracks. In addition, the fixing strength between the conductor **3** and the element body **2** is further improved.

In the embodiments described above, the laminated coil components **1**, **1A**, and **1B** have been described as examples of a laminated electronic component, but the present invention is not limited to these, and can be applied to other laminated electronic components such as laminated ceramic capacitors, laminated varistors, laminated piezoelectric actuators, laminated thermistors, and laminated composite components.

What is claimed is:

1. A laminated electronic component comprising:
an element body having a rectangular parallelepiped shape and formed by laminating a plurality of element-body layers in a laminating direction, the element body having:
a first face;
a second face adjacent to the first face;
a pair of third faces opposed to each other and adjacent to the first face and the second face; and
a depression disposed on the first face and the second face;

a conductor disposed on the element body in the depression and having an L shape, the conductor having an exposed portion exposed on the first face and the second face, the exposed portion including a plurality of divided regions divided by the element body; and a coil including a plurality of coil conductors, wherein a length of each of the divided regions in a dividing direction is longer than a distance with which the plurality of divided regions is separated from each other and longer than a distance with which the exposed portion and the pair of third faces are separated from each other, and a thickness of each of the coil conductors in the laminating direction is less than the distance with which the plurality of divided regions is separated from each other.

2. The laminated electronic component according to claim 1, wherein

the exposed face has a first exposed face exposed on the first face and a second exposed face exposed on the second face, and
the first exposed face and the second exposed face each include the plurality of divided regions.

3. The laminated electronic component according to claim 1, wherein the exposed face is completely divided.

4. The laminated electronic component according to claim 1, wherein the exposed face is divided in an opposing direction of the pair of third faces.

5. A laminated electronic component comprising:
an element body having a rectangular parallelepiped shape and formed by laminating a plurality of element-body layers in a laminating direction, the element body having:
a first face;
a second face adjacent to the first face;
a pair of third faces opposed to each other and adjacent to the first face and the second face; and

15

a depression disposed on the first face and the second face;
 a conductor disposed on the element body in the depression and having an L shape, the conductor having an exposed portion exposed on the first face and the second face, the exposed portion including a plurality of regions separated from each other in an opposing direction of the pair of third faces; and
 a coil including a plurality of coil conductors,
 wherein a length of each of the regions in the opposing direction is longer than a distance with which the plurality of regions is separated from each other in the opposing direction and longer than a distance with which the exposed portion and the pair of third faces are separated from each other in the opposing direction, and a thickness of each of the coil conductors in the laminating direction is less than the distance with which the plurality of regions is separated from each other.
 6. A laminated electronic component comprising:
 an element body having a rectangular parallelepiped shape and formed by laminating a plurality of element-body layers, the element body having:

10 15 20

16

a first face;
 a second face adjacent to the first face;
 a pair of third faces opposed to each other and adjacent to the first face and the second face;
 a fourth face opposed to the second face; and
 a depression disposed on the first face and the second face; and
 a conductor disposed on the element body in the depression and having a broken L shape, the conductor having an exposed portion exposed on the first face and the second face, the exposed portion including a plurality of regions separated from each other in an orthogonal direction orthogonal to an opposing direction of the pair of third faces, the exposed portion being separated from the fourth face,
 wherein a length of each of the regions in the orthogonal direction is longer than a distance with which the plurality of regions is separated from each other in the orthogonal direction and longer than a distance with which the exposed portion and the pair of third faces are separated from each other in the opposing direction.
